SURFACE FINISHING FIXTURE

Russel A. Schultz, Detroit, Mich., assignor to
 Robbins Engineering Company, Detroit, Mich.,
 a corporation of Michigan

Application December 26, 1947, Serial No. 793,895

8 Claims. (Cl. 51—144)

1

The present invention relates to a surface finishing fixture which is particularly adapted for the precision grinding and polishing of a workpiece having curvate surfaces and thin sharp edge portions which would be burned or scored by conventional grinding fixtures.

One type of workpiece which the present invention is particularly adapted to finish is a jet turbine blade comprising a concavo-convex spiral-form airfoil having thin sharp leading and trailing edges extending spirally and longitudinally of the blade at a spiral pitch which varies along the length of the blade. Such a blade is necessarily manufactured from an alloy steel adapted to withstand severe strains and high temperatures and is finished and polished within high precision limits. A plurality of the finished blades are assembled on a jet rotor for rotation at a high angular velocity, so that a slight unbalancing of the rotor, resulting, for example, from lack of precision in the finished blades, will cause undue stress and wear in the turbine bearings.

A problem inherent in the economical grinding of jet turbine blades is that of grinding the spiral surfaces to the high precision required without scoring or burning the thin leading and trailing edges. Consequently, the grinding and polishing of such spiral-form blades in mass production has not heretofore been considered economically feasible by experienced production engineers. Prior to the present invention, such blades have been manufactured by relatively expensive precision casting or precision forging methods, wherein it has been difficult to reproduce the blade within the tolerances required. Checking and inspection of the blades thus formed are difficult and expensive operations, and the percentage of scrap or rejected blades has been high. By means of the present invention, spiral-form turbine blades may be accurately ground and finished within machine tolerances of approximately .002", and the standard part and contour may be economically produced any desired number of times within these limits and with a minimum of scrap or rejected parts.

A primary object of the present invention is to provide a surface finishing fixture suitable for grinding and finishing the curvate contours of jet turbine blades by mass production methods, wherein the blade is economically formed according to a standard size and contour within the high precision limits required and with a minimum of waste resulting from scrap or rejected parts.

2

Other objects of the present invention are to provide a surface finishing fixture adapted for simultaneously traversing and rotating a turbine blade across a flexible abrasive member adapted to conform to and grind the curvate contour of the blade as the latter is brought in contact therewith, to provide means in such a fixture for varying the grinding pressure on the blade according to its thickness so as to avoid scoring or burning the thin edges, and to provide means for automatically indexing the grinding pressure control mechanism in accordance with the spiral contour of the blade as the latter traverses the abrasive surface.

15 Other objects of this invention will appear in the following description and appended claims, reference being had to the accompanying drawings forming a part of this specification wherein like reference characters designate corresponding parts in the several views.

In the drawings:

Fig. 1 is a right end elevation of the fixture embodying the present invention.

25 Fig. 2 is a fragmentary enlarged horizontal section taken in the direction of the arrows substantially along the line 2—2 of Fig. 1.

30 Fig. 3 is a fragmentary front elevation, showing a partial section through the workpiece holder and taken in the direction of the arrows substantially along the line 3—3 of Fig. 2.

Fig. 4 is a fragmentary enlarged vertical section taken in the direction of the arrows substantially along the line 4—4 of Fig. 2.

35 Fig. 5 is an elevation of the broad side of a jet turbine blade which the fixture of the present invention is adapted to finish.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Briefly, the present invention proposes a work holding spindle mounted for moving a curvate workpiece by coordinated rotatable and axial movements across an abrasive member, the latter preferably comprising an abrasive belt running at high speed over a flexible rubber-like mounting wheel adapted to conform to the curvate contour of the workpiece and to provide resiliency at the region of grinding contact. The

work holding spindle is preferably mounted to permit a rocking movement of its axis of rotation toward and away from the abrasive member to permit variation of the grinding pressure on the workpiece and is subject to a constant yielding force tending to move the workpiece toward the abrasive member. In order to avoid scoring or burning of thin portions of the workpiece, the grinding pressure is varied according to the thickness of the workpiece by pressure relief cam means, operating in coordination with the rotation of the work holding spindle for selectively moving the latter away from the abrasive member against the aforesaid yielding force. Thus the axis of a workpiece, such as a turbine blade, having thin edges which would be injured if ground at the full grinding pressure applied at its thicker body portions, is gradually moved away from the abrasive member upon rotation of the thin edges toward the latter.

In the situation of a spiral-form turbine blade, the angular position of the work holding spindle at which the blade's edges approach the abrasive member varies as the blade moves axially. In a preferred embodiment of the present invention, the pressure relief cam, restrained against axial movement, is rotatably mounted on the work holding spindle and rotated therewith by means of a pin projected from the pressure relief cam and adapted to ride in a spiral cam-indexing slot carried by the work holding spindle upon axial movement of the latter. The cam-indexing slot has a spiral pitch corresponding to the spiral pitch of the edge portions of the blade. Thus as the pressure relief cam rotates with the work holding spindle, its angular position is indexed relative to the spindle in accordance with the spiral pitch of the edges of the workpiece as the latter is moved axially across the abrasive member upon axial movement of the spindle.

An embodiment of the present invention particularly adapted for grinding and polishing the curvate surfaces of a spiral-form jet turbine blade is shown by way of example in the drawings and may be used to perform these steps in the method of manufacturing such blades as disclosed in my co-pending application Serial No. 793,064, filed December 22, 1947. As shown in Figs. 1 and 3, a base 10 supports an upright mounting 12 to which is secured a vertical supporting plate 14. A bracket having the forward extending arms 15 and base 16 is secured by the plurality of bolts 17 to the plate 14 and supports a bearing housing 18. A spindle 20, which carries the relatively soft and flexible rubber-like mounting wheel 22, is suitably supported and journaled within the housing 18. The mounting wheel 22, Fig. 2, is secured to the extended left end of the spindle 20 for rotation therewith about a fixed axis and carries the abrasive belt 24 which is driven at a relatively high speed by the lower pulley 26. The latter is rotatably driven by the drive shaft 28 of the motor 30 mounted on the base 10.

The bracket 32 is secured to the vertical plate 14 by a plurality of bolts 33, Fig. 3, and supports the stationary cylindrical sleeve bracket 34, Fig. 2, having its cylindrical axis parallel to the axis of rotation of the mounting wheel 22. A forward extending webbed bracket 36, Fig. 3, reinforced by the lower and upper webs 38 and 40 respectively is mounted on the bracket 32 to support the fixed mounting 42. A cam follower 50, adapted for engagement by a grinding-pressure relief cam to be described in detail below, is held within the

slot 48 of the mounting 42 for rotation about the fixed axis of the pin 44. The pin 44 extends parallel to the axis of the mounting wheel 22 and is secured within the mounting 42 by the set screw 46. The left end of the pin 44 projects from the mounting 42 to support the upright guide 52, which is provided to prevent axial movement of the aforementioned grinding-pressure relief cam and which is secured to the mounting 42 by the screws 54.

Press-fitted within opposite ends of the stationary sleeve bracket 34 are the pair of cylindrical sleeve bushings 56 for rotatably supporting the coaxial and longitudinally extending tube 58. The drive shaft 60, rotatably mounted within and projected from opposite ends of the tube 58, is concentrically spaced therefrom by the cylindrical spacer bushings 62 inserted within opposite ends of the tube 58 to the limit permitted by the annular shoulder 64 of each bushing 62. The right end of the shaft 60 carries the sleeve spacer 66 between the corresponding shoulder 64 and balanced crank arm 67. The latter is suitably secured to the end of the shaft 60 for rotation thereof and is balanced by the handle 68 and ball 69 secured to its opposite ends.

An externally-threaded coaxial sleeve 70 is secured by the pin 72 to the left end of the shaft 60 for movement therewith and, upon rotation of the shaft 60, imparts a screw-driven axial movement thereto by means of a screw-threaded engagement with the stationary internally-threaded nut 74. The latter is secured by the plurality of screws 76 to the sleeve bracket 75, Fig. 2, which in turn is integral with the webbed bracket 77 secured to the vertical supporting plate 14 by the plurality of bolts 78, Fig. 3. Movement-limiting stops 80 and 82 are adjustably screw-threaded on opposite ends of the sleeve 70 and secured thereto in adjusted positions by the set screws 84 and 86 respectively.

A movable sleeve mounting 88 for a workpiece holding assembly is keyed by the key 90 and pin 92 to the tube 58 for rotation and axial movement therewith. Extending laterally from the sleeve mounting 88 as an integral structure thereof is the webbed bracket 94 for the bearing housing 96 which journals and supports the spindle 98 having the pulley 100 secured axially to its leftward extension for rotation therewith. The pulley 100 is suitably driven by a belt 102 which in turn is driven by the pulley 104 mounted on and rotatable with the shaft 60. The pulley 104 is disposed between the adjustable stop 106, secured by the pin 108 to the shaft 60 for rotation therewith, and the sleeve spacer 110 adjacent the left hand shoulder 64.

An idler pulley 112 rides on the belt 102 and is rotatably mounted on the shaft 114 extended through both the left hand web of the bracket 94 and the supporting bracket 116, which latter is pivotally mounted on the tube 58, Fig. 2. Coaxial spacers 118 and 120 are provided around the shaft 114 to suitably space the pulley 112 and bracket 116 and to space the bracket 116 from the adjacent web of the bracket 94. The idler pulley 112 is vertically adjustable by means of the arcuate adjusting slot 122 within the aforesaid left hand web of the bracket 94, Fig. 4, to permit adjustment of the tension of the belt 102. The shaft 114 is clamped in its adjusted position within the arcuate slot 122 by the nut and washer assembly 124.

At the right of the bearing housing 96, Figs. 2 and 3, the spindle 98 is secured to the work

holding spindle 126 for rotation thereof, the latter providing the blade holding jig at its right end, including the detachable clamping member 128 which is interlocked with the end portion of the spindle 126 by means of the interlocking shoulders 132 and 130 of the members 126 and 128 respectively and is clamped in place by the clamping screw 133.

A jet turbine blade 134, illustrating the operation of the present invention, is shown in Fig. 5 and comprises the complex concavo-convex spiral-form airfoil having the longitudinally extending thin sharp leading and trailing edges 135 and 136, and also having the accurately machined dove-tailed base 137, which provides the machined indexing boss 138, and the nib 139 which provides the center hole 140. The base 137 with its boss 138, cooperable with the center hole 140, provide two points of indexing support for the blade 134 to assure its proper alignment within the blade holding jig for rotation about a pre-determined axis during the grinding operation.

In the present instance, the blade 134 is preferably machined by suitable cam guided means to the general airfoil contour, so that grinding to its finished dimensions may be accomplished by a single pass across the high speed rotating abrasive belt 24. The clamping portions of the spindle 126 and the clamp 128 are suitably adapted to index with the boss 138 and to clamp the dove-tailed base 137, upon tightening the clamping screw 133, to permit rotation of the blade 134 about the axis of the center hole 140 and coaxially with the axis of rotation of the work holding spindle 126.

Rotatably mounted on the body of the blade holding spindle 126 is the sleeve 141 which provides the longitudinally extending spiral cam-indexing slot 142 and the relatively short circumferentially extending adjusting slot 143. The latter is adjustable along the clamping screw 144 which secures the sleeve 141 to the spindle 126. Rotatably mounted on the sleeve 141 is the cam sleeve 145 having the annular guide groove 146 which receives the upper extension of the guide member 52, thereby permitting rotational but preventing axial movement of the cam sleeve 145. The cam sleeve 145 provides the axially projecting indexing pin 148 which rides within the spiral cam-indexing slot 142, so as to key the sleeve 145 with the sleeve 141 for rotation therewith and to index the angular position of the sleeve 145 relative to the spindle 126 as the latter moves axially. A pressure relief cam 150, having concavo-convex peripheral portions, Figs. 1 and 3, corresponding somewhat to the concavo-convex surfaces of the blade 134, is also carried by the indexing sleeve 145 and secured thereto by the screws 152, directly over the rotatable cam follower 53 for riding thereon at various angular positions of the cam 150.

With the blade 134 properly clamped by the clamp 128 at the end of the spindle 126 in coaxial alignment with the axis of the spindle 126, phantom view, Figs. 1 and 2, the center pin 154 will be spring-pressed into the indexing hole 140 to provide a second coaxial indexing support for the blade 134. In this position, the blade 134 will be directly over the belt 24 for grinding thereby upon operation of the fixture. The center 154 is secured within the arm 156 and in coaxial alignment with the spindle 126 by the set screw 158. The arm 156 is slidably mounted within the slot 160 of the plunger holder 162, which provides the center bore 164 for receiving the slidable plunger

166, and is secured by the bolt 168 to one end of the plunger 166 for movement therewith parallel to the axis of rotation of the spindle 126. A spring well 170 opens within the other end of the plunger 166, Fig. 2, for the coil spring 172 which abuts the end cover 174 of the plunger holder 162 and coils around the guide stud 176 screw-threaded through the cover 174, the latter being secured to the plunger holder 162 by the plurality of screws 178.

The plunger holder 162 is supported from the webbed bracket 180 which extends from the sleeve mounting 184 as an integral structure thereof. Similarly to the keying of the sleeve mounting 88 to the tube 58, Fig. 4, the sleeve mounting 184 is keyed to the tube 58 by the key 186 and pin 188 for both axial and rotational movement therewith. A lift arm 190 is provided for pivotally raising the bracket 180 and plunger holder 162 about the axis of the tube 58, being pivotally secured to the bracket 180 and plunger 166 by the vertical pivot pins 192 and 194 respectively for pivoting about their vertical axes. The pin 194 projects from the plunger 166 through a longitudinal pin slot, not shown, provided therefor in the upper surface of the plunger holder 162 to permit longitudinal movement of the pin 194 with the plunger 166, and is adapted to support the weight of the entire pivotally mounted blade holding assembly upon pivotally raising the arm 190. The slot 195, provided in the end of the arm 190 for the pin 192, permits a sliding movement of the arm 190 as the distance between the pins 192 and 194 varies upon sliding movement of the plunger 166.

A vertically movable emergency pressure relief plunger 196 is provided directly below the bracket 180 for pivotally raising the latter. The plunger 196 is vertically movable within the sleeve 198 therefor which is supported from the bracket 200 projected from the bracket base 16. The lower portion of the plunger 196 projects through the bracket 200 and is spring-pressed downward by the coil spring 202 which is under compression between the said bracket 200 and stop 204 secured to the lower end of the plunger 196. The lower extremity of the plunger 196 rests on one end of the pivotal lever 206, mounted on the horizontal pivot 208 disposed between the lateral webs of the bracket 15, Fig. 3. On the other side of the pivot 208 from the plunger 196, the lever 206 is pivotally connected at 210 to the coupling 212, which is secured to the tie rod 214 having the coupling 216 secured to its lower end and pivotally connected at 218 to the foot lever 220. One end of the foot lever 220 provides the pedal 222. The other end is pivotally connected at 224 to the base 10.

It is apparent from the structure shown that the sleeve mountings 88 and 184, keyed to the tube 58, and their brackets 94 and 180, together with the bearing support 96, blade holding spindle 126, the plunger holder 162, and center pin 154, are all pivotally movable as a unit with the tube 58 about the horizontal axis of rotation of the shaft 60. The weight of the above pivotally mounted work holding assembly is directed to bear the workpiece 134 downward in grinding contact with the abrasive belt 24. In order to properly determine the maximum grinding pressure, the pivotally mounted work holding assembly is counterbalanced by the weight 228 adjustably mounted on the supporting arm 226 which is secured to the sleeve mounting 88 and projected

radially therefrom oppositely to the aforesaid work holding assembly.

For a clear understanding of the operation of the present invention, it is to be remembered that the sleeve mounting 34 and brackets 15-16, 36, and 77 are stationarily mounted on the upright mounting 12, whereas the sleeve mountings 88 and 184 are keyed to the tube 58 for both rotation and linear movement therewith. The shaft 60 is rotatable within the tube member 58, but by virtue of the continuous sleeve linkages between the stop 106 and the crank arm 67, both secured to the shaft 60, the tube 58 will necessarily move axially with the shaft 60. Upon rotation of the shaft 60, the work holding spindle 126 will be rotated by means of the belt 102, and the lead screw engagement between the threaded sleeve 70 and the stationary nut 74 will drive the shaft 60 and tube 58 axially, resulting in parallel movement of the connected work holding assembly, including the belt 102, spindle 126, and center 154. Thus means are provided for simultaneously rotating and traversing the workpiece 134 relative to the portion of the abrasive belt 24 passing over the rubber mounting wheel 22. The pitch of the screw feed 70 is preferably adapted to move the workpiece 134 axially approximately the distance of the grinding swath of the abrasive belt 24 upon each complete revolution of the spindle 126, so that a new portion of the blade 134 will be continually brought to the grinding position until the entire surface thereof is ground. By virtue of the flexibility of the mounting wheel 22, the abrasive belt 24 thereon readily conforms to the curvate contour of the workpiece 134, and a resiliency is provided at the region of grinding contact.

The relatively thick central portions of the blade 134 present no particular problem in the grinding operation. At such portions, the pressure relief cam 150 does not ride on its follower 50, and the full grinding pressure on the blade 134 is permitted, as determined by the counterbalanced weight of the work holding assembly. As rotation of the blade 134 carries its relatively thick body portions away from the grinding position, and carries either of the thin edges 135 or 136 to the grinding position, the pressure relief cam 150 gradually rides on the rotatable cam follower 50 and gradually rocks the work holding assembly away from the abrasive belt 24 about a pivot axis comprising the axis of rotation of the shaft 60. Thus the grinding pressure is gradually relieved and burning or scoring of the said thin edges is avoided.

Finally as either of the edges 135 or 136 is rotated directly toward the grinding position, the blade 134 is removed completely from contact with the belt 24. Upon continued rotation of the blade 134, its other curvate surface is rotated toward the belt 24 and gradually rocked to the grinding position as the cam 150 rides off the cam follower 50. As the thicker body portion of the blade 134 is rotated to the grinding position, the cam 150 rides clear of the follower 50 and the maximum grinding pressure is again established.

As a consequence of the spiral-form contour of the blade 134, the angular position of the blade 134 at which the edges 135 and 136 are rotated toward the abrasive belt 24 varies with the axial position of the blade 134. It is necessary to index the cam 150 continually in accordance with the pitch of the spiral edges 135 and 136 and the rate of axial movement of the blade 134.

Automatic indexing of the cam 150 is accom-

plished by the pin 148 riding within the spiral cam-indexing slot 142, so that the rotation of the cam 150 is accelerated or decelerated relative to the rotation of the blade 134 upon axial movement of the sleeve 141 and work holding spindle 126 secured therewith. Thus the pressure of the grinding contact is varied in accordance with the body thickness of the workpiece. At the same time, the indexing points for varying the grinding pressure are automatically varied in accordance with the contour of the blade and its axial movement relative to the abrasive belt 24.

To facilitate removal or replacement of a workpiece 134 within the work holding assembly, the center 154 is retractable from the center hole 140 against the tension of the coil spring 172 upon pivoting the lever 190 counterclockwise about the pivot axis 192, Fig. 2. The grinding pressure may be released immediately at any time without recourse to the cam 150 by rocking the entire work holding assembly away from the belt 24, either by stepping on the pedal 222 and forcing the emergency relief plunger 196 upward against the underside of the bracket 180, or by raising the lift arm 190.

It will be seen, therefore, that I have provided a surface finishing fixture suitable for the precision grinding of turbine blades or similar articles having complex spiral-form surfaces and thin edge portions subject to being injured when finished by conventional grinding operations. The fixture described permits the mass production finishing of turbine blades to tolerances of approximately .002", with a minimum of rejects or scrap parts. It permits the finishing of such blades from machined blanks and thus effects a considerable saving in manufacturing costs over precision casting or forging methods by which such turbine blades have been manufactured prior to the present invention.

Although the present invention is illustrated in connection with the grinding of jet turbine blades, it is apparent that the fixture described may be utilized in the finishing of other curvate workpieces presenting problems similar to those involved in the manufacture of high precision jet turbine blades.

Having described my invention, I claim:

1. In a surface finishing fixture adapted for varying the grinding pressure on a workpiece according to the thickness thereof, the combination of an abrasive member for grinding a workpiece in contact therewith, a rotatable and axially movable workpiece holding spindle mounted for yieldingly moving the axis of rotation thereof toward said abrasive member and for traversing a workpiece across said abrasive member by co-ordinated axial and rotatable movements, pressure relief cam means operatively coupled with said spindle for selectively moving the latter away from said abrasive member upon rotation of said spindle, and cam means for indexing said pressure relief cam means relative to the angular position of said spindle upon axial movement of the latter.

2. The combination as claimed in claim 1 and being further characterized in that said pressure relief cam means include a fixed cam follower, and a pressure relief cam rotatably mounted on said spindle and held against axial movement for riding on said cam follower; and said indexing cam means include a cam-indexing slot carried by one of said members comprising said spindle and said pressure relief cam, and a projecting pin

movable along said cam-indexing slot and carried by the other of said two members.

3. The combination as claimed in claim 1 and being further characterized in that the abrasive surface of said abrasive member is flexible and is resiliently supported, and in that said pressure relief cam is adapted to permit maximum grinding pressure at the relatively thick portions of said workpiece and to relieve the grinding pressure at the thinner portions thereof.

4. In a surface finishing fixture, the combination of a rotating abrasive member, a rotatable and axially movable workpiece holding spindle pivotally mounted for rocking the axis of rotation thereof toward and away from said abrasive member for varying the grinding pressure on said workpiece, a lead screw operatively coupled with said spindle for feeding a workpiece held thereby to said abrasive member by coordinated axial and rotatable movements, means for yieldingly rocking the axis of rotation of said spindle toward said abrasive member, a fixed cam follower means rotatably mounted on said spindle and restrained against axial movement for rocking the axis of rotation of said spindle away from said abrasive member as the relatively thin portions of said workpiece are moved to the grinding position and including a pressure relief cam adapted to ride on said cam follower, means to rotatably index said pressure relief cam relative to said spindle upon axial movement of said spindle and including a cam-indexing slot carried by said spindle, and a follower pin projected from said pressure relief cam for riding in said cam-indexing slot.

5. The combination as claimed in claim 4 and being further characterized in that said cam-indexing slot is provided within a sleeve adjustably mounted on said spindle for rotation therewith.

6. A fixture adapted for the precision grinding of the concavo-convex spiral-form surfaces of a jet turbine blade having thin leading and trailing edges extending spirally and longitudinally of the blade, the combination of a rotating abrasive surface for grinding said blade, a longitudinally movable and rotatable blade holding spindle operatively coupled with a lead screw for coordinated axial and rotatable movement relative to said abrasive surface and being pivotally mounted for rocking the axis of rotation thereof toward and from said abrasive surface, means for yieldingly rocking the axis of rotation of said spindle toward said abrasive surface, a spiral indexing-cam slot provided by said spindle and having a spiral pitch corresponding to the spiral pitch of the edges of said blade, a cam sleeve rotatably mounted on said spindle and restrained against axial movement, means for indexing said pressure relief cam in accordance with the longitudinal movement of said blade carried by said spindle and including a pin projected from said cam sleeve for movement along said indexing-cam slot upon longitudinal movement of said spindle, a fixed cam follower, means to rock the axis of rotation of said spindle from said abrasive surface for gradually releasing the grinding pressure on said blade as the thin edges thereof are rotated toward said abrasive surface and including a pressure relief cam adapted to ride on said cam follower and secured to said cam sleeve for rotation therewith.

7. In a surface finishing fixture adapted for the precision grinding of a workpiece having relatively thin portions and relatively thick por-

tions and adapted for varying the grinding pressure on the workpiece to substantially reduce the grinding pressure applied to the thin portions of the workpiece, the combination of an abrasive member for grinding a workpiece in contact therewith, a rotatable and axially movable workpiece holding spindle mounted for yieldingly moving the axis of rotation thereof toward said abrasive member and for traversing a workpiece across said abrasive member by coordinated axial and rotatable movements, a pressure relief cam means operatively coupled with said spindle for controlling the movement of said spindle toward and away from said abrasive member, said cam having a spindle engaging bearing surface providing a contour including portions corresponding to the contour of the thick portions of the workpiece which portions permit relatively high grinding pressures on the thick portions of the workpiece and also including portions which deviate from the contour of the thin portions of the workpiece and move the spindle away from the grinding member to reduce the grinding pressure on the workpiece while maintaining intimate contact therebetween for grinding the thin edge portions of the workpiece, and cam means for indexing said pressure relief cam means relative to the angular position of said spindle upon axial movement of the latter.

8. In a fixture for finish grinding the compound curvate surfaces of a blade having a relatively thick central body portion and thin spiral leading and trailing edges, the combination of a resiliently supported flexible grinding member a blade holding spindle mounted for coordinated axial and rotational movement for traversing and rotating a blade held thereby in grinding contact with said grinding member, said spindle and grinding member being operatively mounted for relative movement therebetween transverse to the axis of rotation of said spindle, means for urging said spindle transversely of its axis of rotation toward said grinding member, and cam actuated grinding pressure control means adapted to prevent scoring of the thin edges of the blade and comprising cam means operatively coupled with said spindle for rotation and coordination therewith and adapted to effect said relative movement between said grinding member and the blade to permit the blade surface to be in grinding contact with said grinding member at a maximum grinding pressure during the grinding of the fixed central portion of the blade and at progressively reduced pressures during the grinding of the thinner portions thereof, and for interrupting the grinding contact between the blade and said grinding member near the periphery of the thin edge portions of the blade whereby said edge portions are held out of grinding contact with said grinding member during rotation of said blade-holding spindle to bring the opposite face of the blade into grinding position, said cam means comprising a fixed cam follower, a sleeve cam rotatably mounted on said spindle for riding on said follower and restrained against axial movement and means to index said sleeve cam rotatably in coordination with the axial movement of said spindle and including a spiral-indexing cam slot provided by said spindle and having a spiral pitch corresponding to the pitch of the spiral edges of said blade, and an indexing pin projecting from said sleeve-cam for movement along said indexing cam slot.

RUSSEL A. SCHULTZ.
